TANK GAUGING HATCH

John M. McDonald, Dubuque, Iowa, assignor to
 A. Y. McDonald Mfg. Co., Dubuque, Iowa, a
 corporation of Iowa

Application February 15, 1932. Serial No. 593,181

7 Claims. (Cl. 220—36)

This invention is concerned with certain improvements in a gauging hatch applicable to a tank for the purpose of providing a normally sealed opening through which a rod or other measuring instrument may be inserted for determining the approximate volume of liquid, such as oil or gasoline, which is contained in the tank. The present hatch may also be combined conveniently with a vent to relieve pressure and vacuum, permitting these two associated devices to be applied to a tank through a single connection.

An exemplification of my invention is set forth in the accompanying drawing in the manner following:

Figure 1 is a vertical section through the present gauging hatch showing its cover in the normally closed position;

Fig. 2, which is a similar view, shows the cover raised to open position;

Fig. 3 is a view in elevation looking toward the hinged end of the gauging hatch cover which is shown in closed position; and

Fig. 4, which is a view similar to Fig. 1, illustrates the gauging hatch operatively combined with a second fitting, here shown as a vent.

From a storage tank T, a pipe or nipple 5 is extended upwardly for threaded connection with the chambered body 6 of the present gauging hatch whose walls may be slightly constricted as at 7 adjacent the upper end which is open in line with the opening in its bottom end where connection is made with the pipe; or the body of the hatch may be connected otherwise to the tank, in any way such as is customary and suitable for the purpose. Mounted over the top opening of the body is a cover 8 having a depending marginal flange 9 fitting over the upper end of the body. A gasket 10 which may take the form of a disk of suitable material is applied to the underside of the cover to which it may be held as by means of a screw 11.

Extending laterally from the body near its upper end are a pair of spaced ears 15. Between these ears is received a heel 18 which is extended laterally and downwardly from the cover. The heel forms one end of a rib 19 having an upwardly inclined cam face extending over the cover. A cam face 20 is provided on the heel, as is also a stop face 21, the latter being engageable with the body when the cover is fully opened. As by means of a pin 22 extending between the two ears 15 and through the heel, the cover is hingedly connected to the body.

In combination with a hatch cover of the kind

described, I provide also a combined locking and operating yoke having opposite arms 25 which are arched over at 26 to join each other and an outwardly extending operating piece 27. The center of the arch formed by the two arms of the yoke lie adjacent the cam surface of the rib so as to engage therewith.

Upon opposite sides of the body, at a point relatively distant from the upper end thereof are bosses 30 into which may be threaded stud screws 31. The shank of each bolt passes also through an eye at the lower end of each arm of the yoke, thereby furnishing a pivotal mounting therefor. The head of each bolt remains spaced from the proximate arm a substantial distance to accommodate upon its shank the coils of a spring 32 one of whose ends 33 is hooked around the proximate arm of the yoke, the other spring end 34 being passed through an opening provided in a lug 35 extending laterally from the body adjacent its base. The effect of the two springs thus provided is to maintain the yoke always in a substantially vertical position against the high end of the cam with which it remains in engagement to press the cover down tightly into closed position over the upper end of the body. If desired, a hole 36 may be formed transversely of the rib adjacent the yoke when in normal position, permitting application of a lock element 37, such as the hasp of a padlock, by which to prevent unauthorized operation of the yoke with consequent opening of the cover.

The present gauging hatch may optionally be incorporated with a second fitting, such as a vent or breather, as suggested in Fig. 4. Here it will be observed that the gauging hatch is identical in all respects with the construction already described, but the body of the hatch is made integral with an extension forming a body also for the vent which may include in its structure a pair of valves 40 and 41 operable in response to plus and minus pressures, respectively, to establish communication between the tank connection and the atmosphere through an opening 42 which faces downwardly below the vent body and to one side of the hatch body.

In operation, the cover may be opened by the application to the yoke of a force which overbalances the tension of the springs which act normally to maintain the cover in tightly closed position. To raise the cover the yoke is swung back to the point where it engages with the heel cam face 20. Further movement of the yoke will force the heel down with a consequent lift of the cover until the lower heel face 21 abuts 110

the body, as indicated in Fig. 2. For these movements, the operating piece 27 may be conveniently actuated by the hand or foot. By maintaining a continued pressure on the yoke such that it will stay in the down position shown in Fig. 2, the cover will remain open, but once this pressure be released, the yoke will spring back, permitting the cover to drop down, and will thereupon slide along the cam 19 toward its high end to force the cover to a tightly closed position. It will be noted, therefore, that the cover, which otherwise is free to swing down, is prevented from returning to closed position until the yoke starts back toward its locking position. In other words, the cover which can be opened either by hand or foot pressure will not stay open one moment after release of such pressure, and its movements and locking are controlled solely by a cam and spring mechanism which alone requires operation to meet all conditions of service.

I claim:

1. A tank hatch in which is combined a body open at the top for closure by a freely hinged cover having a cam on its upper face, a device pivoted to the body swingable in response to tension having means for engaging with the cam to force the cover to a tightly closed position, a releasable locking element insertable through a cover opening for preventing movement of the pivoted device with consequent opening of the cover, and a second cam extending laterally from the cover with which the same means of the pivoted device may engage to swing the cover to open position.
- 35 2. A tank hatch in which is combined a body having a through opening, a freely operable hinged cover forming a closure over one end of the body opening, a cam extending diametrically upon the cover, a yoke pivoted to opposite sides of the body and mounted to swing over the cover to engage the cam thereupon whereby to force the cover with increasing pressure to its closed position, at which point the yoke is positioned transversely of the cover, spring means operating through the yoke for moving the latter to engaging position with the cam, a second cam extended from the cover with which the yoke may engage to raise the cover, and means acting to limit the opening movement of the cover.
- 50 3. A tank hatch in which is combined a body having a through opening, a hinged cover forming a closure over one end of the body opening, a single face cam on the cover, spring actuated inflexible means pivoted to the body engageable with the cam with an increasing pressure to force the cover tightly to closed position and when so engaged being extended transversely of the cover

and longitudinally of the body opening whereby to effectively resist raising of the cover in response to any force proceeding through the body opening, and a second cam device on the cover having a single acting face with which the spring actuated means may engage to raise the cover, the cam device being provided also with means by which to limit the opening movement of the cover.

80 4. A tank hatch in which is combined a body having a through opening, a hinged cover having a cam with a single duplex acting face, and a spring actuated inflexible means carried by the body normally disposed longitudinally of the opening therethrough and coacting with the duplex faces of the cam for successively raising the cover to fully open position and for locking the cover down tight in which position the spring actuated means is in normal position transversely of the cover.

85 5. A tank hatch having a body mounting a freshly operable hinged cover, a rib extending diametrically across the cover upon its upper side and laterally therebeyond forming two oppositely inclined cam faces, a spring-actuated hinged yoke having a single means to engage both cam faces in 90 succession to press the cover to closed position and swing the cover to open position, and means carried by the cover engageable with the body to limit the cover opening movement.

95 6. A tank hatch in which is combined a body 100 having a through opening, a cover hinged to the body and provided with a cam having a single duplex acting face, and spring actuated inflexible means mounted on the body for movement through a fixed path for engagement with the 105 single duplex acting face of the cover at points upon opposite sides of its hinged connection with the body, the cam engaging means being movable to a position which is transversely of the cover when closed at which point it coacts to lock the 110 cover down tight, and being movable to a second position in which it coacts with the cam to hold the cover open.

115 7. A tank hatch in which is combined a body 120 having a through opening, a cover hinged to the body and provided with a cam having a single duplex acting face, and spring actuated inflexible means mounted on the body for movement through a fixed path for engagement with the 125 single duplex acting face of the cover at spaced points only, the cam engaging means being movable to a position which is transversely of the cover when closed at which point it coacts to lock the 130 cover down tight, and being movable to a second position in which it coacts with the cam to hold the cover open.

JOHN M. McDONALD.
